UNITED STATES PATENT OFFICE.

WALTER COX, OF INDIANAPOLIS, INDIANA.

COOLING SYSTEM.

Application filed May 27, 1925. Serial No. 33,252.

To all whom it may concern:

Be it known that I, WALTER Cox, a citizen of the United States, residing at Indianapolis, in the county of Marion and State of Indiana, have invented certain new and useful Improvements in Cooling Systems, of which the following is a specification.

My said invention relates to a cooling system and it is an object thereof to provide a closed tank system which can be used for all sorts of refrigerating work at high temperatures, e. g. from about 20° Fahrenheit to any required temperature above zero.

Referring to the accompanying drawings which are made a part hereof and on which similar reference characters indicate similar parts,

Figure 1 is a plan of my device,

Figure 2, a longitudinal vertical section, 20 and

Figure 3, a transverse section.

In the drawings reference character 10 indicates the frame work of a box or tank or other container or compartment which is to be cooled. This container may be of such a character as is used in creameries, butcher boxes, serum boxes, candy factories, ice cream plants, milk distributors, or any other place where objects or materials are subjected to cooling operations.

Within the container I have shown a group of closed tanks 11. In the present embodiment of the invention these tanks are four in number but it will be understood that any desirable number may be used without changing the character of the invention. The tanks are supported, preferably adjacent the upper corners of the container, by angle irons 12 or by any other devices suitable to the situation, the angle irons in this instance being shown as supported by brackets 13.

Above the tanks is a coil 14 connected to a supply header 15, this coil being carried by angle irons 16 supported by the brackets or posts 13 which support the angle irons 12 on which the tanks rest. As indicated at 17 the coil 14 leads into a tank 11 and in the present instance this tank is connected at 18 to the adjacent tank 11 from the other end of which a pipe leads which pipe connects at 19 to a return header 20.

A pipe 21 leads from the return header to a brine balance tank 22 such as is commonly used in refrigerating plants of large

size. Alternatively the pipe 21 may be connected to a gravity system if preferred.

In the operation of my device the system is operated by any of the various types of brine coolers used in the trade, this brine cooler being connected to the supply header 15 and the return header 20 (or the tank 22) in usual manner. The cooling fluid from the brine cooler enters through the supply header and passes through coil 14 and the pipe 17 to the first tank 11 and through pipe 18 to the second tank, thence by way of pipe 19 to the return header 20, thence to suction of brine pump.

During the entire circulation and therefore throughout the time of use of the device the brine does not come in contact with the atmosphere in the rooms where the tanks or hold-overs 11 are located as each individual return header goes directly back to the brine cooler where the brine is cooled and prepared for another circuit. Absence of contact of the brine with the air in the rooms prevents the atmosphere from taking on odors of calcium and odors from the scum arising in the room, which odors are liable to be taken up by the various goods stored in the rooms. Due to the continuous circulation the temperature in the tanks and coils does not change during the cooling of such substances as high temperature milk and the like and thus a rapid rate of cooling is kept up.

It will be understood that the tanks are closed and they are intended to work under pressure of from 5 to 10 pounds. Under these conditions every square foot of the surface of the tanks is a cooling surface. This fact permits the tanks to be relatively small and thus permits a better air circulation throughout the rooms or boxes. The direct circulation from the brine coolers to the tanks keeps the system full of brine. By the arrangement shown the brine machine may be run only a few hours each day and then shut down the balance of the twenty-four hours. Under such conditions there is but little change in temperature during the twenty-four hours after the rooms have once been cooled down to the desired temperature. This possibility of operating the system efficiently while running the brine cooler only a few hours reduces the cost of operation by 25 to 30 per cent below that of the open tank and coil system. In addition to

this a longer hold-over and a more even temperature hold-over is secured during the time that the machine is shut down than with the open tank system.

5. The system of baffles for control of the air can be arranged for either central upward passage of the warm air or central downward passage of the cold air, as will be understood by those skilled in the art. The
 10. coils 14 may be increased in number or may be omitted according to the work to be done. The tanks may be changed in size and shape and many other changes may be made as will be obvious to those skilled in the art
 15. all without departing from the spirit of the invention, the true scope of which is indicated in the appended claims.

Having thus fully described my said invention, what I claim as new and desire to
 20. secure by Letters Patent, is:

1. A refrigerating system comprising a closed refrigerating compartment, a coil supported in an upper corner of said compartment, connections from the ends of the
 25. coil to the source of supply, hold-over tanks or brine cylinders interposed in series with

said coil adapted to contain a supply of cooling brine for maintaining the temperature approximately uniform during intervals of inactivity of the system, substantially as set forth. 30

2. A refrigerating system comprising a closed refrigerating compartment, a plurality of coils supported in upper corners of said compartment said coils being connected in series, a header connecting one coil to a source of refrigerant and another header leading back from another coil to said source of refrigerant, closed hold-over tanks or brine cylinders associated with said coils 35
 40 adapted to contain a supply of cooling brine for maintaining the temperature approximately uniform during intervals of inactivity of the system, and a brine balance tank in communication with the connection between a pair of coils, substantially as set forth. 45

In witness whereof, I have hereunto set my hand and seal at Indianapolis, Indiana, this 25th day of May, A. D. nineteen hundred and twenty-five. 50

WALTER COX. [L. S.]
